Lyman E. Dodge.
ATTORNEY

UNITED STATES PATENT OFFICE.

WILLIAM H. B. LAVARACK, OF HAVERSTRAW, NEW YORK, ASSIGNOR TO RAILROAD
ACCESSORIES CORPORATION, OF NEW YORK, N. Y., A CORPORATION OF NEW YORK.

SEMAPHORE BLADE.

Application filed February 28, 1924. Serial No. 695,661.

To all whom it may concern:

Be it known that I, WILLIAM H. B. LAVARACK, a citizen of the United States, and resident of Haverstraw, county of Rockland, and State of New York, have invented a new and useful Semaphore Blade, of which the following is a specification.

This invention relates to railway signalling and particularly to semaphores and more especially to what are known as semaphore blades.

The principal object of this invention is to provide a device serving as a semaphore blade and support therefor which will be extremely simple in construction and inexpensive to manufacture, install and maintain.

Other objects and advantages will appear as the description of the particular physical embodiment selected to illustrate the invention progresses, and the novel features of the invention will be particularly pointed out in the appended claims.

In describing the invention in detail and the particular physical embodiment selected to illustrate the invention, reference is had to the accompanying drawing, wherein I have illustrated a particular preferred physical embodiment of my invention, and wherein like characters of reference designate corresponding parts throughout the several views, and in which:

Figure 1 is a front elevational view of a semaphore blade embodying my invention; Fig. 2, is a bottom plan view of the device as shown by Fig. 1; Fig. 3, is a cross sectional view on the plane indicated by the line III—III of Fig. 2 viewed in the direction as indicated by the arrows at the ends of the line.

Applicant's new and improved semaphore blade is particularly adapted for use as what are known as dwarf blades, that is, semaphore blades which are attached to and supported by operating mechanism situated between two parallel trackways. In such situations the blade is supported not more than two or three feet from the ground and must be of a length such that it does not project into and beyond the clearance of the equipment which is operated upon the trackway.

As the available space is extremely limited in which these dwarf signal blades are often placed and as the operating mechanism is not always positioned exactly the same distance from the gauge line of a rail, it is nec-

essary at times in order to bring a blade within the available space to shift what might be called its center of rotation or oscillation. This necessity requires that the semaphore blade should preferably be so made, that is, without any alterations on the ground, may be assembled with its support so as to oscillate on that center which is such that both its ends will be within the available clearance space.

In the drawing, Fig. 1 illustrates a dwarf semaphore blade designated 1. This blade as shown is preferably tapered, being somewhat wider at one end than it is at the other end. In the form shown the blade is made of a single piece of sheet metal by bending the longitudinal sides downwardly as viewed in Fig. 1, so that as shown best by Fig. 3, the sides as 2 and 3 make an angle somewhat less than a right angle with the underside of the blade 1 as shown in Fig. 3 that is, with the back of the blade. The construction as shown makes the blade substantially a tapered channel and in the preferred form the face of the blade is enamelled so as to prevent as much as possible the adherence of dirt and soot to the face of the blade so as to obscure the color thereof which is generally an arrestive color such as white, red or yellow.

In order to support this semaphore blade upon the operating mechanism so that irrespective of the distance of the operating mechanism from the gauge of the adjacent rail, the blade will still be within the clearance space available, the applicant has formed the orifices as 4, 5, 6 and 7 in one channel side and corresponding orifices aligning in the other channel side. These orifices serve to receive fastening means preferably bolts as 8 and 9 and serve to attach to the blade a U shaped member 10 as best shown in Fig. 3.

The orifices 4, 5, 6 and 7 may be considered to be formed in pairs as 4 and 5, 5 and 6, and 6 and 7. The U shaped member 10 may be attached by the bolts as 8 and 9 so as to be positioned at the pairs 4 and 5 or 5 and 6 or 6 and 7 so that three different centers of oscillation of the blade 1 are provided so that the blade 1 may be positioned so as to be properly placed in the clearance space.

The U shaped member 10 is formed of a single piece of preferably metal of suitable

weight and is of such rigidity that the sides thereof 11 and 12 may be fairly readily caused to approach or recede from one another so that the two legs or sides 11 and 12 of the **U** shaped member may be made to fit snugly against the sides 2 and 3 regardless of the position of the member 10 longitudinally of the blade 1.

The **U** shaped member 10 as is well understood, is supported in any of the usual or appropriate manners on an operating mechanism and applicant has indicated the orifices 13 and 14 as serving for this purpose although it is not meant to exclude the use of one orifice only positioned centrally of the **U** shaped member.

Although I have particularly described the construction of one physical embodiment of my invention, and explained the operation and principle thereof, nevertheless, I desire to have it understood that the form selected is merely illustrative, but does not exhaust the possible physical embodiments of the idea of means underlying my invention.

What I claim is new and desire to secure by Letters Patent of the United States, is:

1. In a semaphore blade, in combination; a single sheet of metal formed into a channel and formed with a plurality of paired orifices in one channel side aligning with a like plurality in the other channel side and a substantially **U** shaped support formed with paired orifices in one leg and a similar aligned pair in the other leg and means whereby the support may be attached to the channel at any one of the paired orifices.

2. In a semaphore blade, in combination; a single piece of sheet material formed into

an approximate channel longitudinally tapered; a substantially **U** shaped support and means for attaching the support to the sheet material at any one of a plurality of positions longitudinally of the sheet material.

3. In a semaphore blade, in combination; a single piece of sheet material formed into an approximate channel longitudinally tapered; a support and means for attaching the support to the sheet material at any one of a plurality of positions longitudinally of the sheet material.

4. As a semaphore blade a sheet of metal formed throughout its length into a substantially somewhat longitudinally tapered channel supported solely by the channel sides.

5. As a semaphore blade, a single sheet of metal formed into a substantially somewhat tapered channel having the channel sides bent to form somewhat less than a right angle with the bottom of the channel said sides forming a sole means for supporting the blade.

6. As a semaphore blade, a single sheet of metal formed into a substantially somewhat tapered channel having the channel sides bent to form somewhat less than a right angle with the bottom of the channel, said sides being formed with orifices for attachment and a substantially **U**-shaped member forming the sole means of support joined by means of said orifices.

7. In a semaphore blade, a support, and a channel formed with means for attaching the support at a plurality of positions longitudinally of the channel.

WILLIAM H. B. LAVARACK.
